UNITED STATES PATENT OFFICE

167,944

UTILITY CLIP FOR AUTOMOBILES

Edward R. Kolenda, Oak Lawn, and Victor V.
Postillion, Cicero, Ill.

Application December 12, 1951, Serial No. 17,704

Term of patent 7 years

(Cl. D14—6)

To all whom it may concern:

Be it known that we, Edward R. Kolenda, a citizen of the United States, and resident of Oak Lawn, in the county of Cook and State of Illinois, and Victor V. Postillion, a citizen of the United States, and resident of Cicero, in the county of Cook and State of Illinois, have invented a new, original, and ornamental Design for Utility Clip for Automobiles, of which the following is a specification, reference being had to the accompanying drawing, forming part thereof.

Fig. 1 is a side elevation;
Fig. 2 is a front elevation;
Fig. 3 is a rear elevation; and
Fig. 4 is a perspective view of a utility clip for automobiles, showing our new design.

We claim:

The ornamental design for a utility clip for automobiles, substantially as shown.

EDWARD R. KOLENDA.
VICTOR V. POSTILLION.
